SWING

Melvin W. Hunt, Gardena, Calif.

Application August 11, 1944, Serial No. 549,039

1 Claim. (Cl. 155—65)

1

The present invention relates to new and useful improvements in swings for children and has for its primary object to provide foot operated means adapted to produce the swinging motion of the swing.

An important object of the present invention is to provide a novel attaching bracket by means of which the swing may be suspended from a cross-bar of either square shape in cross section or of a tubular formation.

A further important object of the invention is to provide a swing of this character adapted for operation by little exertion and which at the same time is strong and durable in construction, relatively inexpensive to manufacture, and otherwise well adapted for the purposes for which the same is intended.

Other objects and advantages designed in the details of construction and operation are more fully hereinafter described and claimed, reference to be had to the accompanying drawing forming part hereof, wherein like numerals refer to like parts throughout and in which:

Figure 1 is a side elevational view;

Figure 2 is a front elevational view and

Figure 3 is a detail of a modified clamping construction for attaching the swing supporting bracket to a tubular or transversely rounded support.

Referring now to the drawing in detail and first with respect to the following invention illustrated in Figures 1 and 2 of the drawing, the numeral 5 designates an attaching bracket generally, which includes the lower clamping block 6 and an upper clamping block 7 connected respectively below and above a crossbar 8 by means of bolts 9. The opposed faces of the blocks 6 and 7 are recessed to snugly receive the crossbar as shown to advantage in Figure 1 of the drawing.

A pair of plates 10 extend downwardly from the opposite sides of the lower clamping block 6, the plate 10 thus being disposed in face parallel relation and a pin 11 extends transversely of the plate 10 at their lower edges on which a bushing 12 is journaled.

A pair of bars 13 are secured at their upper ends on the bushing 12 and are suspended downwardly therefrom in face parallel relation and have horizontally extending seat supporting brackets 14 attached adjacent the lower ends of the bars 13, the brackets 14 extending laterally from one side of the bars 13 and have a seat 15 attached at their outer ends. Brackets 16 extend from the brackets 14 immediately in front of the seat and are attached to the bars 13 above the brackets

2

14. Hand grips 17 are carried by the braces 16. A pivot pin 18 is attached at the lower ends of the bars 13 and to which a walking beam 19 is pivotally attached intermediate the ends of the latter, the walking beam having a foot support 20 attached at one end and having a link 21 pivotally attached at its upper end and extending upwardly at an inclined angle between the bars 13 and pivotally attached at its upper end to a bracket 22 attached to the lower clamping block 6 by bolts 23.

The walking beam 19 is pivoted off center with its shorter end attached to the link 21 and its longer end having the foot support 20 attached thereto, the foot support being positioned under the bracket 14 of the seat and in position for engagement by the foot of a child when occupying the seat.

Accordingly, in the operation of the device, a downward pressure exerted on the foot support 20 of the walking beam 19 causing an upward force to be exerted on the short end of the walking beam which, being transmitted to the stationary bracket 22 by the link 21 will cause a swinging of the seat supporting bars 13 in one direction and upon releasing of the foot pressure on the walking beam 19 the bars 13 and the seat attached thereto will gravitate in an opposite direction and thus produce a pendulous swinging action.

In Figure 3 of the drawing, I have illustrated a clamping structure for attaching the swing to a tubular cross member 24 by means of a plate 25 securing to the lower clamping block 6 by bolts 26, the plate 25 having a lower clamping member 27 carried thereby attached to an upper clamping member 28 by means of the bolts 29 for clamping engagement with the tubular cross-bar 24. Set screws 30 and 31 carried by the upper and lower clamping members respectively engage the crossbar to secure the clamping member against rotary movement thereon.

It is believed the details of construction, manner of operation and advantages of the device will be readily understood from the foregoing without further detailed explanation.

Having thus described the invention, what I claim is:

A swing comprising a transverse pair of upper and lower horizontal attaching members, means for detachably connecting the members respectively above and below a horizontal supporting beam, a pair of spaced parallel brackets extending downwardly from the lower one of said attaching members, a third bracket detachably secured

to and extending downwardly from said lower attaching member in offset relation to said pair of brackets, a pendulous bar pivoted at its upper end to said pair of brackets and having a seat supported thereon at its lower end and laterally projected so as to be disposed normally beneath said third bracket in a plane extending vertically through said bracket, and means carried by the bar and connected to said third bracket for actuating the bar swingably, said means includ-

ing a walking beam type of lever pivotally attached to the lower end of the bar and provided at one of its ends with means for engagement by the feet of an occupant of the seat and the opposite end of said lever being pivotally attached to said third bracket by a link extending normally in an angularly crossed relation to said bar.
